[57] CLAIM

The ornamental design for a packaging tray for food or the like, as shown and described.

DESCRIPTION

FIG. 1 is a top perspective view of a packaging tray for food or the like showing my new design;

FIG. 2 is a bottom perspective view showing the side and end not seen in FIG. 1;

FIG. 3 is an end elevational view thereof;

FIG. 4 is a top perspective view showing a modified form of my new design;

FIG. 5 is a bottom perspective view showing the side and end not seen in FIG. 4;

FIG. 6 is an end elevational view;

FIG. 7 is a side elevational view thereof;

FIG. 8 is a top perspective view showing still another modified form of my new design;

FIG. 9 is a bottom perspective view showing the sides not seen in FIG. 8; and

FIG. 10 is a side elevational view thereof.
